(57) **CLAIM**

We claim the ornamental design for a gas burner, as shown and described.

DESCRIPTION

FIGS. 1-8 illustrate a first embodiment of the gas burner in which:

FIG. 1 is a perspective view showing the gas burner on an example cooktop.

FIG. 2 is a perspective view of the gas burner;

FIG. 3 is a top view thereof;

FIG. 4 is a bottom view thereof;

FIG. 5 is a front view thereof;

FIG. 6 is a left side view thereof;

FIG. 7 is a rear view thereof; and

FIG. 8 is a right side view thereof.

FIGS. 9-15 illustrate a second embodiment of the gas burner in which:

FIG. 9 is a perspective view of the gas burner;

FIG. 10 is a top view thereof;

FIG. 11 is a bottom view thereof;

FIG. 12 is a front view thereof;

FIG. 13 is a left side view thereof;

FIG. 14 is a rear view thereof; and,

FIG. 15 is a right side view thereof.

Broken lines are used in the drawings to illustrate environment and features of the gas burner that form no part of the claimed design. Dot-dash lines are used in the drawings to represent environmental features that are broken away to better visualize features of the design, and form no part of the claimed design.
